(57) **CLAIM**

The ornamental design for an exercise bar with platform, as shown and described.

DESCRIPTION

FIG. 1 is a perspective view of the exercise bar with platform showing my new design;

FIG. 2 is a left-side view thereof;

FIG. 3 is a right-side view thereof;

FIG. 4 is a front elevation view thereof;

FIG. 5 is a rear elevation view thereof;

FIG. 6 is a top elevation view thereof;

FIG. 7 is a bottom elevation view thereof; and,

FIG. 8 is an in-use view thereof.

The broken lines shown in the drawings illustrate portions of the exercise bar with platform that form no part of the claimed design.

1 Claim, 6 Drawing Sheets---
